UNITED STATES PATENT OFFICE.

ALBERT F. PLOCK, OF PITTSBURGH, PENNSYLVANIA.

SINTERING PLANT.

1,330,090.

Specification of Letters Patent. Patented Feb. 10, 1920.

Application filed April 27, 1915. Serial No. 24,213.

To all whom it may concern:

Be it known that I, ALBERT F. PLOCK, a citizen of the United States, residing at Pittsburgh, in the county of Allegheny and State of Pennsylvania, have invented a new and useful Sintering Plant, of which the following is a specification.

My invention relates to apparatus used in sintering finely divided materials, and more particularly relates to apparatus for use in sintering finely divided iron bearing materials such as blast furnace flue dust.

One object of my invention is to provide sintering apparatus having novel means whereby the sintering cars are handled or manipulated in the sintering operations.

Another object of this invention is to provide sintering apparatus having sintering cars of novel construction whereby warping of the cars is prevented and loss of heat by radiation is avoided and overcome, the life of the cars is greatly lengthened, and the cost of upkeep is materially lessened.

Another object of my invention is to provide sintering apparatus having means whereby sticking of the sintered material to the grate bars of the sintering cars is avoided and overcome.

A further object of the invention is to provide a sintering plant of novel construction which is adapted for use in restricted quarters and in localities not affording room to construct sintering plants as made heretofore.

Still further objects of my invention will be disclosed hereinafter and specifically pointed out in the claim.

Referring now to the drawings forming part of this specification, Figure 1 is a plan showing sintering apparatus constructed and arranged in accordance with my invention.

Fig. 2 is a sectional side elevation of the sintering plant shown in Fig. 1.

Fig. 3 is an end elevation of the apparatus shown in Figs. 1 and 2.

Fig. 4 is a sectional plan taken on the irregular line IV—IV of Fig. 5, showing the feeding mechanism by which the finely divided flue dust or other materials are delivered from the distributing hoppers into the sintering cars.

Fig. 5 is a sectional side elevation of the feeding mechanism shown in Fig. 4, and on a smaller scale in Figs. 1 and 2.

Fig. 6 is a sectional elevation showing a detail in the construction of the tilting track

rails of the hoist forming part of my improved sintering apparatus.

Fig. 7 is a similar sectional elevation showing the construction of the guide for the tilting track rails.

Fig. 8 is a sectional side elevation showing the construction of the tilting track rails on the hoist at the discharge end of the sintering track.

Fig. 9 is a plan showing the construction of sintering cars made in accordance with my invention and forming part of my improved sintering apparatus.

Fig. 10 is a longitudinal sectional side elevation showing the construction of the sintering car of Fig. 9.

Fig. 11 is a sectional end elevation of the sintering car shown in Figs. 9 and 10, and on a smaller scale in Figs. 1, 2 and 3.

In the accompanying drawings the numeral 2 designates the building in which the sintering operations are effected, and located at one end of the building 2 are storage bins 3 for materials to be sintered. At the other end of the building 2 is a rotary car dumping mechanism 4 by which the sintering cars 5 are inverted to discharge sintered materials therefrom into cars 6 positioned on the track 6^a located beneath the car dumping mechanism.

Extending lengthwise within the building 2 from one end to the other thereof is an elevated sintering track 7, and beneath the track 7 is an inclined return track 8 on which the empty sintering cars are delivered from the car dumping end to the opposite end of the building 2.

A hoist 9 comprising a platform 10 having track rails 11 and a fluid pressure cylinder 12 having a plunger 13, is employed to connect the discharge end of the return track 8 with the car receiving end of the sintering track 7, the platform 10 being mounted on the upper end of the vertically moving plunger 13. Vertical guides 14, 14, are provided for the platform of the hoist 9, and a bumper 15 affords means for stopping the cars in hoisting position upon the platform 10.

A similarly constructed hoist 16 at the car dumping end of the sintering track 7 connects the discharge end of the sintering track with the receiving end of the return track 8.

The hoist 16 comprises a platform 10 and a fluid pressure cylinder 12 with a plunger

13 connected at its upper end to the platform 10, and vertical guides 14, 14, secured to the frame of the building 2 engage opposite sides of the vertically movable platform. The track rails 17, 17, of the hoist 16 are pivotally secured at one end by U-bolts 18 to the platform 10, (as is best shown in Fig. 6) and guides 19 on the platform having lugs 20, 20, (see Fig. 7) form a seat 10 for the flange of the track rails 17 which permits of a limited vertical movement of the tilting rails 17, 17.

The free ends of the rails 17, 17, project outwardly so as to engage with the bracket 21 on the beam 22 extending between the columns 23, (as is shown in Fig. 8), and as the platform of the hoist 16 reaches its lowermost position, as shown in full lines in Fig. 2, the rails 17 are tilted and a car 5 supported thereon is caused to run by gravity to the rails of the return track 8.

The rails of the return track 8 are inclined downwardly toward the discharge end thereof. The sintering cars when transferred thereto from the hoist 16 will continue to move thereon by gravity until upon the rails 11, 11, on the platform 10 of the hoist 9, in position to be lifted and again transferred from the hoist 9 to the sintering track 7.

30 The return track 8 is carried upon beams 22 which extend between columns or supports 23, 23, and the sintering track 7 is carried on beams 24 framed to the ends of the floor beams 25 which are supported on columns 23 and 23.

Suspended within the building 2 near one end thereof is a double hopper having compartments 28 and 29 with the discharge outlets 30 and 31 thereof above and closely adjacent to the tops of the sintering cars 5 which pass thereunder on the track 7 when being filled with the flue dust or other materials to be sintered.

The compartments 28 and 29 have a rotary feed regulating mechanism in the lower end thereof by which the quantity of material and the speed at which the material is fed into the successive sintering cars are regulated and controlled. This mechanism as shown consists in the sliding gates 32 and 33, for regulating the quantity, and rotating shafts 34 and 35, each shaft having a series of radial arms 36 thereon which turn within the openings at the lower end of the compartments to regulate the speed at which the materials are discharged into the cars 5 as the cars are passed under the compartments of the hopper. The shaft 34 has a sprocket wheel 37 rotatably secured on one end thereof which is detachably connected to its shaft by means of a clutch 37^a. As shown the shaft 35 has a sprocket wheel 38 keyed or otherwise fastened thereon, and the sprocket wheels 37 and 38 are connected by sprocket chains 39 and 40 to sprocket wheels 41 and

42 on the jack shaft 43. This jack shaft is positively rotated in any desired manner, preferably through the sprocket wheel 43^a by means of an electric driving motor (not shown).

70 On the platform 44 above the bins 28, 29, is a moistening pug mill 45, and at one side of the pug mill platform 44 is an elevator 46 having a discharge spout 47 arranged to deliver the finely divided sintering materials 75 to the elevated platform 44, or when necessary or desirable, into the pug mill 45. In such case discharge outlets will be provided on the pug mill 45 having sliding gates or shutters to close the outlets, to discharge materials from this pug mill directly into the hopper 28, or hopper 29.

80 The lower end of the elevator 46 has a boot into which materials from the mixing pug mill 48 are discharged, and these materials 85 are received and delivered into the pug mill 48 by an endless belt conveyer 49 which is located below and at one side of the storage bin 3.

90 The storage bin 3 has bottom discharge outlets 51, 52, 53, which are arranged to deliver materials upon the endless belt conveyers 54 of which there is one beneath each of these outlets of the bin 3, and these endless belt conveyers 54 discharge materials deposited thereon upon the conveyer 49 which discharges into the dry pug mill 48. Track rails 55, 55, on the trestle 56 beneath which the storage bin 3 is located provide means for supplying and unloading materials to be 100 sintered to the storage bin 3.

95 At the opposite end of the building 2 of the sintering plant is the rotary car dumping mechanism 4 which is arranged to receive and invert the sintered materials therefrom into the car 6 positioned beneath the car dumping mechanism on the lower track 6^a.

105 The dumping mechanism, which may be of any desired known type, as shown is formed 110 of two annular tracks or rings 58, 58, mounted on supporting rollers so as to turn, and having a rope 59 connecting one of these rings with a drum 60 on the shaft 61 which is mounted in bearings 62, 63, at one side of 115 the car dumping mechanism. The shaft 61 is connected by reducing gears 64, 65, with a driving pulley 66 which in turn is connected by an endless belt (not shown) with a jack shaft or other prime mover.

120 Beneath the sintering track formed by the rails 3, 3, is a windbox 68 having a throat 69 on its upper side which is provided with a slot or opening 70 in the upper end thereof. Connected to one side of the windbox are two 125 branch flues or offtakes 71, 71, which lead to the flue 72 extending into the inlet on the rotary fan 73. The discharge outlet of the fan 73 is connected by a flue 74 to the stack 75, which is located adjacent to the fan on the 130

outside of the building 2. A driving motor 76 is directly connected to the shaft 78 of the fan 73 to actuate the fan when the sintering plant is in operation.

5 Cleaning doors 77 are provided on the windbox 68 for removing the finely divided material carried thereinto from the sintering cars 5 by the products of combustion passing through the windbox from the sintering cars to the stack 75.

Positioned within the building 2 above the sintering track 7, is the ignition furnace 78 by which the materials in the successive cars 5 are ignited and the combustion of the materials in the cars is started.

10 The ignition furnace 78 is bottomless and comprises side and end walls and a roof or top lined with refractory material. The sintering cars 5 form the bottom of the ignition furnace as they successively pass beneath the furnace on the track 7 in igniting the materials therein.

15 The series of sintering cars 5 (the construction of which is shown in detail in Figs. 9, 10 and 11) are arranged to travel from one end to the other of the sintering track 7 and to be positioned on the hoists 9 and 16 while being transferred from the sintering track 7 to the return track 8, and from the track 8 to the sintering track 7. Each sintering car is separated by perforated grate bars into an upper compartment for materials being sintered, and a lower compartment or windbox 79. The windbox 79 has a slot 80 in the bottom thereof which extends lengthwise parallel with the length of the car.

20 Flanged wearing plates 81 are secured on the lower or outer surface of the bottom plate of the cars 5, and these wearing plates have slots or openings 82 therein registering with the slot or series of slots 70 in the wear plate on the upper end of the throat 69 of the windbox 68 beneath the sintering track 7. Supports 83 are provided at an intermediate point in the height of the cars 5 on the sides and ends thereof to secure in position within the cars the removable perforated or slotted grate bars 84 forming the support within the cars for the materials being sintered.

25 The slotted grate bars 84 are made in sections and extend lengthwise across the width of the furnace, one end of these bars being interlocked with the bridge or grate bar support 85 which extends lengthwise within the windbox of the car at the middle of its width, and the other end of the grate bars 84 being detachably fastened in place to prevent displacement of the grate bars when the cars are inverted in dumping sintered material therefrom.

30 Each of the cars 5 is provided on its interior with a removable metal lining for the side and end walls thereof, this lining being formed in sections and comprising cast metal plates 86 having ribs 87 on one side thereof

which hold the plates at a distance apart from the sides and ends of the car. Preferably the space 88 between the lining plates and side and end of walls of the car is packed with finely divided fire clay or other refractory material. An air space 88 may be provided, however, by omitting the refractory material, when desired.

35 The lining plates 86 have countersunk holes therein in which the countersunk heads 75 of the bolts 89 are secured in fastening the lining plates 86 in position. The bolts 89 as shown have slots in their outer ends in which a key 91 is inserted to provide for the quick detachment of the bolts in removing and replacing the lining plates. Ordinary screw threaded bolts and nuts may be substituted for the slotted bolts and keys, when desired, to fasten the lining plates 86 in place.

40 The axles or stub shafts 92 for the cars 5 are fastened to the sides and bottom of the cars as shown, and the four wheels 93 are secured to the stub shafts in the usual known manner. When the cars 5 are traveling on the sintering track 7 the wearing plate 81 90 on the bottom of the cars engages with the slotted wearing plate 94 on the upper end of the throat 69 of the windbox 68 so as to prevent ingress of air to the windbox 68.

45 The operation of my improved sintering plant will now be described:

50 Flue dust sintered with my improved apparatus usually contains so much carbon that the intense heat of the sintering operation causes the sintered materials to adhere to a considerable extent to the bottom plates or grate bars of the sintering cars. To overcome this tendency, finely divided iron ore or other material which contains little or no carbon is spread in a layer of about one inch 100 in thickness on the grate bars 84 before the flue dust, mill scale, or other mixture of iron bearing and carbonaceous materials is put into the cars. The ore is put into the compartment 29 of the hopper, and the flue dust, 110 mill scale, or mixture of iron oxid containing carbon, is placed in the second compartment 28.

55 Part of the compartments of the storage bin 3 having been filled with flue dust, mill 115 scale, or a mixture of such materials, and one of these compartments with finely divided ore or other iron bearing material containing less carbon than is contained in the flue dust, the conveyers 49 and 54 are 120 started so as to deliver the desired material to the dry pug mill 48. The materials entering this pug mill are discharged into the boot of the elevator 46 and are carried upwardly thereby, being discharged upon the 125 elevated platform 44.

60 Materials intended to be dry are then transferred into the hopper 28 or 29, depending upon its composition. When to be moistened, as is usually the case, water is 130

supplied to the pug mill while the materials are shoveled or otherwise delivered thereto, and after being mixed and moistened such materials are discharged therefrom 5 into the hopper 28 or 29, as has been described.

A sufficient number of cars to fill the elevated sintering track 7 is then positioned thereon, and a car 5 also is placed on the 10 platform 10 of the hoist 9. The sintering cars, as they pass beneath the discharge outlet on the suspended hopper 29 receive a small quantity of iron ore or similar non-carbonaceous material, or of a mixture of 15 materials having a small percentage of carbonaceous material, which is spread in a layer of about one inch in thickness on the bottom of each car as it passes beneath the discharge opening 31 of the hopper 29.

20 The paddles or arms 36 on the constantly rotating shaft 35 of the hopper 29 are driven at a speed which will regulate the flow of material from the hopper 29 so as to deliver a layer of the requisite thickness in the bottom of the cars.

25 As the car passes beneath the discharge opening 30 in the hopper 28 it receives the flue dust or other mixture of iron oxide and carbon to be sintered, the feed from the hopper 28 being regulated so as to practically fill the body of the car 5 above the grate bars while the car is being moved from one end to the other beneath the outlet 30.

30 The car 5 is then moved forwardly (or 35 from right to left in Fig. 2) and another car is brought into position beneath the outlets of the hoppers 28 and 29, and in passing thereunder receives first a layer of non-carbonaceous material and then the flue dust, in 40 the same manner as has been described. When a third car 5 is passed beneath the hoppers 28, 29, the first filled car will become positioned underneath the sintering furnace 78 in which the material to be sintered is ignited and its combustion started.

45 In igniting the material in the first filled car, the fan 73 driven by the motor 76 is started so as to exhaust the air or other gases from the windbox 68 beneath the sintering track 7 and draw out the air through the flues 71, 72, finally discharging the withdrawn products of combustion into the stack 75.

50 The series of gas burners with which the sintering furnace 78 is provided supply the heat necessary to start or promote combustion of the flue dust in the cars successively placed therein.

55 Each of the cars 5 forms a down draft furnace and while any particular car is passing beneath the ignition furnace 78 the uppermost surface of the material therein is thoroughly ignited. The fan 73 connected through the flues 71 and 72 with the windbox 68 beneath the sintering track draws

the products of combustion downwardly through the body of material within the cars 5 and discharges the withdrawn products of combustion into the stack 75.

When clear of the ignition furnace 78 the 70 cars 5 are still connected by the slots or openings 80 in the bottom thereof with the registering slot in the throat 69 on top of the windbox 68 so that the down draft continues and the sintering operation is promoted from the top toward the bottom of the materials in the cars.

The layer of iron ore, or of iron bearing material having a considerably smaller percentage of carbonaceous material, will not 80 be sintered as readily as the flue dust which contains more carbon, and in this way the sintering operation is completed while the sintered material is not burned or sintered to the grate bars 84 supporting the sintered 85 material within the cars.

The plate lining 86 on the sides and ends of the cars being out of contact with the car and having a refractory material in the space between the lining plates and car, the 90 intense heat of the body of sintered material is not transmitted to the sides of the car, and sticking of the sintered material to the sides of the car also is prevented, while radiation of heat through the side and end walls of 95 the cars is overcome.

Other cars are then successively passed beneath the hoppers 28 and 29 and beneath the sintering furnace 78 until the track 7 is entirely filled with cars.

100 In the plant shown, six of the cars 5 are maintained on the sintering track 7, and one or more additional cars will be located on the hoists 9 and 16 and on the lower inclined return track 8 connecting the hoists beneath 105 the sintering track.

When a car is pushed or moved from the platform 10 of the hoist 9 to the receiving end of the sintering track 7, a car will be moved from the sintering track to the platform 10 of the hoist 16. This car will then be pushed forwardly upon the track rails 110 of the car dumping mechanism.

The car dumping mechanism is then actuated so as to invert the car 5 in position 115 thereon, and in this way discharge the sintered material in the inverted car into the car 6 positioned on the track 6^a below the car dumping mechanism. The dumping mechanism is then rotated to again bring 120 the car into upright position, or into position to be transferred backwardly into position on the tilting track rails of the platform 10 of the hoist 16.

125 The hoist 16 is then lowered to bring the car 5 on its platform into position to be discharged upon the track 8. As the platform 10 approaches the lowered position shown in Fig. 2 the projecting ends of the track rails 17 pivoted on the platform will engage with 130

the ledge or bracket 21 on the columns 23 at one side of the platform, and further downward movement of the platform causes these rails to be inclined at sufficient angle to effect a forward movement of the car by gravity and cause this car to move onto the inclined track 8. The rails of the track 8 are inclined downwardly sufficiently for the cars 5 to move by gravity until they reach the platform 10 of the hoist 9, the cars being brought to a stop on the hoist 9 by striking the bumper 15 provided for that purpose at the lower end of this track.

The empty sintering car now on the platform of the hoist 9 is then raised until the platform 10 is in the dotted position shown at the right in Fig. 2, and this car is then moved from the platform to the sintering track 7 into position to receive a fresh charge of material to be sintered from the hoppers 28 and 29.

When a car 5 is moved from beneath the hoppers 28 and 29, another car is moved from beneath the ignition furnaces 78 while the car at the discharge end of the sintering track 7 is moved upon the platform of the hoist 16. Each car, as the sintering operation is completed, is discharged from the sintering track to the track rails of the hoist 16, and such car is moved upon the dumping mechanism 4. Its contents are then removed by dumping the car, and such car, after being dumped, is replaced on the platform of the hoist 16 and is lowered by this hoist into the position shown in full lines in Fig. 2, from which position it is discharged by gravity and is caused to travel on the inclined return track 8 until in position on the platform 10 of the hoist 9.

The above described operations are then repeated intermittently with the successive cars so as to cause a substantially continuous sintering operation.

In continuing the operation of the sintering plant the materials to be sintered are delivered into the compartments of the storage bin 3, and these materials are transferred on the conveyers 54 and 49, and elevator 46, to the pug mills, and are delivered into the distributing hoppers 28 and 29. The successive cars are filled, the filled cars are ignited, and the materials therein are sintered and removed from the cars as has been described.

The advantages of my invention will be appreciated by those skilled in the art. The apparatus is simple and compact and requires a minimum floor space. The necessity for using transfer tracks at the ends of the sintering track in positioning the cars is avoided and made unnecessary.

Modifications in the construction and arrangement of the parts may be made without departing from the invention as defined in the appended claim.

I claim:—

In a sintering plant the combination of an elevated sintering track, a series of sintering cars arranged to traverse said track during the sintering operations, means at the ends and beneath said sintering track for transferring said cars from the discharge to the receiving end of the said sintering track, means at the receiving end of the sintering track for filling the cars with sintering materials and means at the delivery end of said sintering track for inverting said cars to remove sintered materials therefrom preparatory to transferring the empty cars to the receiving end of said sintering track.

In testimony whereof, I have hereunto set my hand.

ALBERT F. PLOCK.

Witnesses:

R. D. LITTLE,
WILLIAM B. WHARTON.
